US00D585146S

(12) **United States Design Patent**
McCarthy

(10) **Patent No.:** **US D585,146 S**
(45) **Date of Patent:** **** Jan. 20, 2009**

(54) **STAINED GLASS**(75) Inventor: **Jessica Marie McCarthy**, Belton, TX
(US)(73) Assignee: **JELD-WEN, inc.**, Klamath Falls, OR
(US)(**) Term: **14 Years**(21) Appl. No.: **29/303,575**(22) Filed: **Feb. 12, 2008**(51) **LOC (9) Cl.** **25-01**(52) **U.S. Cl.** **D25/103**(58) **Field of Classification Search** **D25/103-111,
D25/52, 48, 138; D6/306, 470, 494; D26/122;
D21/494; 428/38, 49; 52/204.59; 362/330**

See application file for complete search history.

(57) **CLAIM**

The ornamental design for a stained glass, as shown and described.

DESCRIPTION

FIG. 1 is an elevation view of a stained glass of the present invention; and,

FIG. 2 is a perspective view thereof.

The broken lines in the drawings depict environmental subject matter and form no part of the claimed design.
